SHOW CASE LIGHT ASSEMBLY

Application filed April 14, 1930. Serial No. 444,922.

This invention relates generally to show case light assemblies and constitutes an improvement upon the constructions set forth in my pending application filed October 2, 1929, Serial No. 396,852.

In the accompanying drawings:

Figure 1 is a top plan view of a show case with parts broken away showing clips and tie rods embodying my invention applied thereto;

Figure 2 is a perspective view of one of the clips;

Figure 3 is a view similar to Figure 2 but showing the stamping B in another position for receiving a light;

Figure 4 is a fragmentary perspective view of the central assembly of lights and showing an intermediate clip applied to said lights;

Figure 5 is a fragmentary perspective view of a corner assembly of the structure illustrated in Figure 1;

Figure 6 is a view similar to Figure 4 showing the clip applied to two lights instead of three;

Figure 7 is a view similar to Figure 5 but showing the assembly at the opposite end of the case;

Figure 8 is a fragmentary perspective view of the intermediate clip with the stamping B removed therefrom;

Figure 9 is a view similar to Figure 8 showing the clip applied to two lights instead of three;

Figure 10 is a fragmentary vertical sectional view through a slightly modified form of construction;

Figure 11 is a fragmentary transverse sectional view through the case taken on the line 11-11 of Figure 1.

Referring now to the drawings, 1 and 2 respectively are upright lights arranged edge to edge and forming the front wall of a show case; 3 and 4 respectively are upright lights arranged edge to edge and forming the rear wall of the show case; 5 is an upright light extending between the lights 1 and 3 at the outer edges thereof and constituting an end wall of the case; 6 is an upright light extending between the lights 2 and 4 at the outer edges thereof and constituting another end

wall of the case; 7 is an upright partition extending between the lights 1 and 3 adjacent their inner edges; 8 is a substantially horizontal light above the upright lights aforesaid and constituting the top wall of the case; 9 is a clip embodying my invention uniting the lights 1, 2, 7 and 8 respectively; 10 is a similar clip uniting the lights 3, 4, 7 and 8 respectively; 11 is a slightly modified clip uniting the lights 1, 5 and 8; 12 is a clip similar to 11 uniting the lights 2, 6 and 8; 13 is a clip similar to 11 uniting the lights 3, 5 and 8; 14 is a clip similar to 11 uniting the lights 4, 6 and 8; 15 is a tie rod terminally connected to said clips 9 and 10; 16 is a tie rod terminally connected to the clips 11 and 13; and 17 is a tie rod terminally connected to the clips 12 and 14.

With reference to the clips 9 and 10, each preferably comprises two stampings A and B respectively connected together by tubular rivets C. As shown, the stamping A comprises a substantially rectangular base 18, a pair of downwardly opening laterally aligned channels 19 and 20 having the bases 21 and 22 thereof in horizontal alignment with and projecting laterally from opposite edges of the base 18 intermediate the ends thereof, a rearwardly opening channel 23 rising above the base 18 at the forward end thereof, and a depending L-shaped portion 24 at the rear end of the base. The stamping B comprises a downwardly opening channel 25 and a flat portion 26 extending laterally from one side of the channel portion at the lower edges thereof. The rivet C extends through the base 27 of the L-shaped portion and through the lateral portion 26. When the parts are assembled the base 28 of the channel 25 is in horizontal alignment with the bases 18, 21 and 22, and the channel 25 may be swung to the right or left of the L-shaped portion 24. Thus clips constructed as described are capable of substantially universal use. For example, such clips may be interchangeably used on the front and rear walls of the case by merely swinging the channel portion 25 to the proper position to receive the partition 7. As shown, the laterally spaced channels 19 and 20 of the clip 9 receive the upper edges 100

of the lights 1 and 2 at the meeting edges thereof, while the channel 25 receives the upper edge of the partition 7. However, as the channel portions 19 and 20 are in alignment such portions may receive the upper edge of a single upright light 30 intermediate its ends (Figure 6) and the channel 25 may be shifted to right or left of the L-shaped portion 24 to receive the upper edges of a transversely extending partition such as 31. Thus the clip is capable of use at the meeting edges or intermediate the edges of the upright lights. Moreover, such a clip may be used at a corner of a case to hold the lights 1, 5 and 8. 15 As shown in Figure 5, the channel 19 has been cut off from the base 18 and the channel 25 has been swung to the left of the L-shaped portion 24. In Figure 7 the channel 20 has been cut off and the channel 25 has been 20 swung to the right of the L-shaped portion 24. It is also apparent from Figure 8 that the stamping A alone may be used to unite adjacent upright lights 33 and 34 and a horizontal light 35, or as illustrated in Figure 9, may be 25 used intermediate the ends of the upright light 40 to unite the latter and a top light 41. The tie rods 15, 16 and 17 are identical in construction and each preferably comprises two sections D and E connected at their inner ends by a turnbuckle F and having depending hook portions 42 and 43 for engagement with the tubular rivets C. Thus when the parts are assembled the rods serve as braces between the front and rear walls 30 of the case. Due to the construction and arrangement of the lateral and L-shaped portions 26 and 24 respectively and of the rivets C and tie rods, the hook portions 42 and 43 have a swivel connection with the clips and 35 will be held by the top light 8 against accidental displacement from the rivets. Thus sufficient play is provided between the rods and clips to prevent the clips from rocking upon the lights when the turnbuckles are adjusted. Should the clips be used without the 40 L-shaped portions 24 and stampings B, as illustrated in Figure 10, a short plate 50 may be welded to the base 18 and may be provided with a suitable opening 51 for receiving 45 hooked portions of the tie rods.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

60 1. A clip of the class described formed of only two stampings, swivelly connected together, one of said stampings having a base for supporting a show case light and provided at certain edges of the base with means 65 for holding show case lights, the other stamp-

ing also having means for holding a show case light.

2. In a show case construction, the combination with top, end and front lights, of a clip at the juncture thereof comprising a member extending beneath said top light and having a return-bent end portion engaging said top light, an integral depending U-shaped portion engaging the edge of said front light, and a U-shaped member pivotally connected to said first member and engaging the edge of said end light.

3. In a show case construction, the combination with upright lights arranged at substantial right angles to one another and a top light, of a clip at the juncture thereof comprising a member extending beneath said top light and having a return-bent end portion engaging the edge of said top light, a U-shaped member pivotally connected to the other end of said first member and engaging the edge of one of said upright lights, and a depending U-shaped member arranged intermediate the ends of said first member and integral therewith and engaging the edge of the other upright light.

4. In a show case construction, the combination with a pair of upright lights arranged edge to edge, an upright light arranged at a substantial right angle thereto and a top light, of a clip at the juncture thereof comprising a member extending beneath said top light and having a return-bent end portion engaging the edge of said top light, a pair of depending U-shaped members upon opposite sides of said first member and integral therewith and engaging the edges of said pair of upright lights, and a U-shaped member pivotally connected to said first member and engaging the edge of said other upright light.

5. In a show case construction, the combination with upright lights arranged at substantial right angles to one another, and a top light, of a clip at the juncture thereof comprising a member extending beneath said top light and having a return-bent end portion engaging the edge of said top light, means intermediate the ends of said first member for engaging the edge of one of said upright lights, said first mentioned member having its other end arranged below the general plane of said member, and a U-shaped member pivotally connected to the said end of said first member and engaging the edge of the other upright light, the top edges of said upright lights being in the same plane.

6. In a show case construction, the combination with top, transverse and front lights, of a clip at the juncture thereof comprising a member extending beneath said top light and having a return-bent end portion engaging the edge of said top light, a depending U-shaped portion engaging the edge of said front light, and a U-shaped member pivotally connected to said first member and engaging the edge of said end light.

connected to the other end of said member and engaging the edge of said transverse light, the pivotal connection between said first member and U-shaped member being provided with an opening extending axially therethrough for receiving a portion of a tie member.

In testimony whereof I affix my signature.
LEO W. KENNEDY.
